UNITED STATES PATENT OFFICE.

PHILIP A. MYERS, OF ASHLAND, OHIO, ASSIGNOR TO THE F. E. MYERS & BROTHER CO., OF ASHLAND, OHIO, A CORPORATION OF OHIO.

COMBINED PUMP HEAD AND POWER HEAD.

Application filed January 12, 1925. Serial No. 1,861.

This invention relates to improvements in combined pump heads and power heads for use in connection with water pumps, particularly of the deep well type adapted 5 for domestic and other uses.

The present invention is in the nature of an improvement upon the power head casing and pump head set forth in Letters Patent granted to me and issued to my then 10 assignee, The F. E. Myers & Brother Company, No. 1,385,141 dated July 19, 1921, for improvements in pumping apparatus. In that patent the pump head and the casing of the power head are connected by means 15 of bolts, flanges and a shoulder. In the present invention the power head casing is provided with a projecting support formed of two parts or members, one of them preferably made integral with the casing, and the 20 other secured thereto by detachable means so that one member of the support may be removed for the insertion into the other member of the pump head and its drop pipe.

This support may be readily machined on 25 its upper face and within it so that it may be made perfectly true and thus be adapted to accurately position the pumping mechanism proper so as to cause the pump rod to travel in a perfect right line prepositioned 30 to agree with the position and line of travel of that member of the operating mechanism within the power casing which is connected with the pump rod to actuate it.

And the provision of making this support 35 in two detachable members facilitates the insertion of the pump head and attached parts upon and into the support, and at the same time readily enables the assembler to 40 secure the pump head and its parts upon and in the support by connecting the removable member of the support to the fixed member after the parts have been assembled.

In the accompanying drawings forming a 45 part of this specification:

Figure 1 is a vertical sectional view of a power head casing, a pump head and attached parts and my improved pump head support.

Figure 2 is a horizontal section of the casing and plan view of the pump head and its parts, as also a plan of the two-member support.

Figure 3 is a like view to Figure 1 showing a modified form in which the drop pipe 50 is placed within the support instead of the

pump head but extended to fit within the support as in Figure 1.

Figure 4 is a plan view of what is shown in Figure 3 except that the power casing 60 is in horizontal section.

Referring to the drawings in detail, the numeral 1 designates a power head casing preferably made of cast iron, and adapted to receive within it some form of power head mechanism, such for instance, as that shown and set forth in my said former Patent, No. 1,385,141, dated July 19, 1921, referred to above; or such as shown in my application, Serial No. 750,926, filed November 19, 1924. This power mechanism, of whatever 70 type, is designed to impart reciprocating motion to the pump or piston rod which forms a part of a deep well pump which is the type of pump that is to be supported by this power head through the instrumentality 75 of my improved support.

This support comprises a member designated 2 and another indicated at 3. The member 2 is preferably secured to the power head casing 1 by being cast integral therewith, though it may be otherwise connected to the casing. It projects outward from the casing and on its upper face constitutes a surface or shoulder 4 upon which the pump head is to fit and rest. This member of the support is further fashioned with a circular recess 5 which in connection with a similar formation 6 on the detachable member 3, constitutes a circular opening within which the power head may fit as in Figure 1, or 80 within which a part of the drop pipe may be fitted as in Figure 3.

By means of fastening devices, preferably in the nature of bolts 7, which may be stud bolts about which the member 2 of the support is cast, and nuts 8, the detachable member 3 of the support may be secured to and detached from the member 2, as clearly indicated in Figure 2. The size of the circular opening is such that the parts will 95 clamp the lower portion 9 of the power head 10, as shown in Figure 1, or will clamp the upper portion of the drop pipe 11, as shown in Figure 3. In either case the pump head constitutes a hollow shell into which the water is delivered by the pumping mechanism and thence discharged through any convenient pipe line attached to the head by means of the screw-threaded neck 105 12. This pump head may be made of the 110

form shown in Figure 1 with the extension 9 to fit within and be clamped by the members of the support and to rest upon the support as indicated at 4; or the pump head may be made to rest upon the support as indicated at 4^a in Figure 3 and the drop pipe 13 be fitted within the support and be clamped and held thereby.

The pump head may further be provided 10 with a cap 14 into which is screwed an upper cylinder 15 within which operates the upper section 16 of the pump rod equipped with a piston or plunger 17, as shown in Figure 1; or instead, may be equipped with 15 a conventional stuffing box as shown at 18 in Figure 3 adapted to make a water-tight joint between the pump head and the piston or pump rod 16^a as also shown in that figure.

The drop pipe, whether connected to the 20 extension 9 of the pump head 10 as in Figure 1, or connected to the body of the pump head as shown in Figure 3, is conventional in character and is adapted to extend down into a well and to support the lower cylinder 25 of the pump.

It will now be seen that I have provided a two-part pump head support in combination with a power head casing, and that one member of this support may be readily removed for mounting on and within the support the pump head and drop pipe and be likewise readily reconnected with the other member so as to complete the support and effect a clamping action by which the pump 30 head and drop pipe are securely held and accurately positioned in the proper place to bring the piston or pump rod into the required vertical plane to agree with the plane in which will travel the actuating part of 35 the operating mechanism, so that this actuating part will not tend to deflect the rod from its line of movement. It is a material matter to effect the automatic correct positioning of the piston or pump rod with respect to the power mechanism within the 40 casing by the mere act of assembling the pump head and drop pipe with the support.

It is a further material matter to be able to readily machine the upper surface and the interior of the support so as to insure this 50 accurate positioning of the parts when assembled. These pumps are made in large quantities at the works of my assignee, and the interest of the public requires that they be produced economically so that they may 55 be sold at reasonable prices; and the further interest of the public requires that the power head and pump head may be readily assembled at the place of use in suchwise that the piston or pump rod will be properly 60 positioned, as before stated, and in suchwise also that the pump head and drop pipe shall be firmly maintained in position when once 65 assembled so that the structure will continue to operate with facility and efficiency. 65

The leading characteristic of this invention resides in the combined two-part support, one part connected with the power head casing and the two parts detachably connected together and forming, when assembled, a support and clamping device by which the pump head and drop pipe are positioned and secured. 70

It will be understood that I desire to comprehend within my invention such modifications as may be necessary to adapt it to varying conditions and uses. 75

Having thus fully described my invention, what I claim as new and desire to secure by Letters Patent of the United States, is: 80

In a device of the character described, the combination with a power head casing, of a support formed with two parts, one part being integral with the casing and the other part detachably secured thereto, said parts 85 having opposite recesses which constitute a circular opening, and a pump head having an extension with a shoulder at the juncture of the head and extension, such shoulder being adapted to rest upon the support and such 90 extension to fit within said recesses.

In testimony whereof, I affix my signature.

PHILIP A. MYERS.
